UNITED STATES PATENT OFFICE.

WILLIAM F. KIESEL, JR., OF ALTOONA, PENNSYLVANIA, ASSIGNOR TO PENNSYLVANIA RAILROAD COMPANY, OF PHILADELPHIA, PENNSYLVANIA, A CORPORATION OF PENNSYLVANIA.

TANK-CAR.

SPECIFICATION forming part of Letters Patent No. 790,690, dated May 23, 1905.

Application filed October 20, 1904. Serial No. 229,234.

To all whom it may concern:

Be it known that I, WILLIAM F. KIESEL, Jr., a citizen of the United States, residing at Altoona, in the county of Blair and State of Pennsylvania, have invented certain new and useful Improvements in Tank-Cars, of which the following is a specification.

This invention relates to improvements in the underframes for tank-cars; and the object of my improvements is to provide a steel construction of the frame wherein the body-bolsters and intermediate cross-bearers will constitute also the saddles upon which the tank rests.

15 A further object is to provide certain improvements in the details of construction of the body-bolsters and cross-bearers and also in the manner of bracing and strengthening the members of the underframe, as will appear more fully hereinafter.

I attain my objects by means of the arrangement and construction of the several parts of the framework, as illustrated in the accompanying drawings, in which—

25 Figure 1 represents a divided sectional and end view of a tank-car frame embodying my improvements, the sectional half being taken on a medial line through one of the body-bolsters; Fig. 2, a detail showing a divided section, one half of which is taken on a medial line through one of the cross-bearers and the other half on a line struck across the center of the car; Fig. 3, a broken plan view of one-half of the car-frame; Fig. 4, a vertical longitudinal section through one end of the underframe of the car; Fig. 5, a side elevation of the underframe extending from the center of the car to and including one of the cross-bearers; Fig. 6, a detail showing a vertical 35 section of the end-block brace-plate on the line $z z$ in Fig. 3; Fig. 7, a vertical transverse section of a body-bolster on the line $x x$ in Fig. 1, and Fig. 8 a similar section of a cross-bearer on the line $y y$ in Fig. 2.

40 Like numerals refer to like parts in the several views.

The center sills 1 1 are formed of heavy steel channel-bars with the flanges turned

outward. These center sills run the entire length of the car and are supported upon the 50 wheel-trucks, so that the entire weight of the car is carried by them. The couplers at each end of the car are also attached to these center sills, and all pulling strains and compression shocks are transmitted directly thereto. 55 At each side of the center sills are light channel-bars 2 2, having their flanges turned inward, the function of these side sills being to form spacers and longitudinal braces for the ends of the bolsters and cross-bearers and 60 also supports for the footboards which run along each side of the tank. At each end the side sills are cross-connected by end sills 30, formed of heavier channel-bars, with the flanges turned outward, the end sills being 65 secured to the side sills and center sills by suitable angle-plates or castings riveted thereto. The center sills are connected at the top by a cover-plate 3, which runs the entire 70 length of the car-frame between the head-blocks 23.

The body-bolsters are formed by two pairs of vertical plates 4 cut in the form illustrated more clearly in Fig. 1 and having flanges 22 pressed outward along the inner, lower, and 75 outer edges. The lower edges of these bolster side plates are inclined upward from the center and are riveted to a bottom cover-plate 5, which passes across beneath the center sills and part way out toward the ends of the bolster side plates. Between these side plates and passing across the center sills above the center cover-plate 3 is a cover-plate 6, which is riveted to the under side of the angle-bars 7, which also pass across the center sills and 80 are riveted to the inner sides of the side plates 4. At their outer ends the side plates are narrowed down to the depth of the side sills 2, to which they are attached by means of the flanges 22 and the angle-plates 8. 85

Passing over the reduced portions of the side plates 4 and projecting beyond the side sills 2 are longitudinal plates 9, which extend from one end of the car to the other on each side of the tank, forming the footboards. 95 These footboard-plates are supported by the

side sills, to the upper flange of which they are riveted, and they are strengthened along their outside and inside edges by the light angle-bars 10 and 11. On account of the 5 length these footboard-plates must be made in sections, the joints thereof being located at the center lines of the body-bolsters and cross-bearers, where the sections are united by means of the splice-plates 12, the inner 10 portion of the footboard-plates at these points resting upon angles attached to the side plates of the body-bolsters and cross-bearers. At intermediate points between the cross-bearers and bolsters the inward 15 side of the footboard-plate is supported by bracket-bars 45, as shown in Fig. 2.

Above the angle-bars 7 the side plates 4 project in a triangular form, the outer edges of these triangles being strengthened by the 20 angle-bars 13, which run down the outside of the plates, and the inner or upper edges being curved to conform with the shape of the tank which is to be supported upon the underframe. Along these curved edges and between 25 the side plates are riveted curved inverted angle-bars 14, by which depressed flanges are formed on the inside of the plates, on which rest hard-wood blocks 15, which project above the edges of the plates and 30 form the bed for the tank, their function being to prevent the tank from rubbing against any metal part of the underframe, thereby avoiding the constant wearing away of the tank-shell, which would otherwise take place. 35 Additional bearing-blocks 16 are provided above the center sills, said blocks being positioned between the angle-bars 7.

Between the center sills and on a line with the bolster side plates 4 are flanged plates 17, 40 which are riveted to the center sills and to the top and bottom cover-plates, thereby forming continuations of the side plates through the center sills and providing practically continuous side plates for the bolsters 45 extending from side sill to side sill across the car-frame. To the under side of the bottom cover-plate 5, which is widened out at the center, (see Figs. 3, 4, and 7,) is secured the center bearing-plate 18, which rests upon the 50 wheel-truck.

At the outer ends of the body-bolsters between the side plates 4 are fastened inclined eye-plates to receive bolts 20, to which the straps 21, which pass over the tank, are attached by means of turnbuckles and by 55 means of which the tank is held securely in place upon the saddles.

At each end of the car are located hard-wood head-blocks which pass transversely 60 across the center sills, to which they are attached by means of bolts 33. These head-blocks are cut away to conform to the shape of the tank ends, thereby forming sockets for the ends of the tanks to prevent endwise motion upon the underframe. At the outer

ends these head-blocks are secured to longitudinal vertical plate-braces 24, which project forward from the body-bolsters. These plate-blaces are secured to the body-bolster side plates by means of pairs of vertical angles 27 and to the head-blocks by similar pairs of angles 26. The lower edges of the plate-braces are also riveted to pairs of longitudinal angle-bars 25, which extend between the body-bolsters and the end sills 30, to which latter they are secured by means of angle-plates 29. The ends of the head-blocks also rest upon these angle-bars 25 and are secured thereto by bolts 34. The end thrust on the head-blocks is taken up by the angle-braces 80 28, riveted to the angle-bars 25, and also by a central brace 32, formed of a heavy casting riveted to the center sills. It will be seen that these longitudinal plate-blaces and angle-bars, extending as they do between the 85 body-bolsters and the head-blocks and end sills, perform the function of stiffening the bolsters and end sills, thereby preventing distortion of the underframing at the ends where the greatest strains occur. 90

On the line $z z$ the plate-blaces 24 are perforated to allow the passage therethrough of strap-bolts 20, the heads of which rest against inclined eye-brackets 31, (see Figs. 4 and 6,) these eye-brackets being located adjacent to 95 the points where the brace-plates are attached to the head-blocks, whereby I am enabled to place securing-straps around the tank close to the ends to hold the tank firmly in place upon the head-blocks. 100

As the angle-bars 25 are spaced apart a distance sufficient to admit the passage therebetween of the bolts 34 by which the head-blocks are secured thereto, I provide between said angle-bars and the lower edges of the brace-plates 24 spacing-strips 35 (see Fig. 6) in order to rivet the angle-bars to the brace-plates. This spacing apart of the angle-bars also carries them each side of the vertical angles 27, by which the brace-plate is 105 riveted to the bolster, and I am thereby also enabled to rivet the angle-bars to said vertical angles, thereby forming a rigid attachment between the outer bolster-plate 4, the brace-plates 24, and angle-bars 25. 110

Equally dividing the space between the body-bolsters are two cross-bearers, one of which is shown in position in the plan view in Fig. 3. These cross-bearers are formed of two pairs of side plates 36, similar in shape to the bolster side plates; but they are different from the bolsters in that they do not have the top and bottom cover-plates. The inclined lower edges of these cross-bearer plates are secured on the inside to angle-bars 38, which 120 pass completely across the frame from one side sill to the other beneath the center sills. Angle-bars 37 also pass horizontally across between the side sills above the cover-plate 3 and are riveted to the inside of the plates 125 130

36. Above these horizontal angle-bars the plates 36 project in triangular shape, the outer inclined edges being stiffened by the angle-plates 13 and the inner curved edges being provided with inverted angles 14 to receive bearing-blocks 15, the same as in the case of the bolster-plates, central bearing-blocks 16 being also provided above the center sills between the angle-bars 37. The outer ends of these cross-bearer plates are reduced, so as to be secured to the side sills, to which they are fastened by means of out-turned flanges 39 and angle-plates 8. The inner edges of the plates 36 are also provided with out-turned flanges 39, which are riveted to the center sills. Eye-plates 19 are also riveted between these cross-bearer side plates to receive strap-bolts 20, as in the case of the bolsters.

20 Between the body-bolsters the center sills are stiffened along the inside lower edges by the inturned angle-bars 40. The cross-bearer angle-bars 38 where they pass beneath the center sills are riveted to these angles 40.

25 At the center of the underframe is a stirrup-plate 41, to the upturned ends of which are bolted the eyebolts 42, which are attached by turnbuckles to the rods 43, which pass up around the tank and are coupled to the yoke 44, which encircles the dome, thereby holding the tank from turning upon the frame-saddles. By reason of this construction it will be seen that the body-bolsters and cross-bearers are rendered comparatively light in weight and yet of sufficient strength and stiffness to serve their purpose and that the center sill construction also provides strength and stiffness sufficient to support and withstand all stresses due to the weights carried thereby or to the pulling and compression strains to which it is subjected. The bearing-blocks 15 and 16 are shaped on their upper surfaces to fit the contour of the tank where it rests upon the bolsters and cross-bearers, and shells of different diameter may therefore be readily fitted to an underframe of this construction. While I prefer to form the side plates for the body-bolsters and cross-bearers with the flanges 22 and 39 pressed out therefrom, it will be evident that these flanges may be formed by angle-bars riveted to the edges of said plates. The pressed flange, however, gives a stronger construction and is therefore preferred. Other changes in the details of construction, arrangement, and combination of the several parts may also be made without departing from the spirit of my invention.

60 Having thus described my invention, what I claim as new, and desire to secure by Letters Patent, is—

1. The combination, with the side sills of a car, of tank-supporting saddles terminally connected to the side sills and comprising the

side plates of the body-bolsters, said saddles having curved upper edges.

2. The combination, with the side sills of a car, of saddles connected to the side sills and comprising the side plates of the body-bolsters, said saddles having relatively deep portions and relatively shallow portions, the relatively deep portions being provided at their upper edges with curved seats for the reception of the tank.

3. The combination, with the side sills and center sills of a car, of saddles connected to the side sills and center sills and arranged in pairs, said saddles having inwardly-disposed flanges and outwardly-disposed flanges.

4. In a car, the combination, with side sills and center sills, of saddles connected to the side and center sills and extending below the side sills and above the center sills, inwardly-disposed flanges at the upper edges of the saddles, and outwardly-disposed flanges at the lower edges of the saddles.

5. A car having a body-bolster and tank-supporting saddles comprising the sides of the bolster with inwardly and outwardly disposed flanges.

6. The combination with the side sills of a car, of tank-supporting saddles terminally connected to the side sills and comprising the side plates of the body-bolsters.

7. A car including tank-supporting saddles comprising plates arranged in pairs and having inwardly-disposed flanges and outwardly-disposed flanges.

8. A car having tank-supporting saddles comprising plates provided with inclined lower edges, outwardly-disposed flanges carried by the lower edges of the plates, a cover-plate connected to the outwardly-disposed flanges and curved upper edges provided with inwardly-disposed flanges forming seats for a tank.

9. The combination, with the side sills of a car, of plates carried by the side sills and comprising tank-supports, and footboard-supports carried by said plates.

10. In a car, the combination, with the side sills and the center sills, of a bolster having side plates extending above the side sills and center sills to receive a tank.

11. The combination, with the side sills and center sills of a car, of a bolster having portions extending above the side sills and center sills to receive a tank, and top and bottom cover-plates below the upper edges of the bolster sides.

12. A car-bolster having side plates, the lower edges of which converge from the sides toward the middle of the car, said plates having ends inclined in an upward direction toward the center of the car and provided with curved upper edges.

13. The combination, with the side sills and end sills of a car, of tank-supporting bolsters extending from side sill to side sill, cen-

ter sills interposed between the bolsters, and tank-supporting plates extending from the side sills to the center sills.

14. In a car-frame, the combination, with 5 the side sills, of tank-supporting saddles terminally connected to the side sills and comprising vertical plates having triangular projections rising at each side of the center above the level of the side sills, said projections having 10 their inner edges curved and their outer edges inwardly inclined.

15. In a car-frame, the combination, with 15 the side sills, of tank-supporting saddles terminally connected to the side sills and comprising vertical plates having triangular projections rising at each side of the center above the level of the side sills, said projections having 20 their inner edges curved and their outer edges reinforced by bars which pass down upon the body of said plates.

16. In a car-frame, a tank-supporting saddle comprising pairs of vertical transverse plates spaced apart and having their upper edges curved, inturned curved flanges on said 25 plates below said edges, and bearing-blocks resting on said flanges between the plates.

17. In a car-frame, the combination, with 30 the center sills, of a tank-supporting saddle comprising pairs of vertical transverse plates projecting from opposite sides of the center sills, horizontal inturned angle-bars passing across the center sills and attached to the inner sides of the opposite members of each pair of plates, said plates projecting above 35 said angle-bars and having their upper edges curved, inturned curved flanges on the plates below said edges, and bearing-blocks resting upon said flanges between the plates and over the center sills between the angle-bars.

- 40 18. In a car-frame, the combination, with the center sills and side sills, of a bolster comprising vertical side plates having portions rising above the side sills and center sills to receive a tank, bottom cover-plates passing 45 across beneath the center sills and attached to the lower edges of said side plates, and top cover-plates passing across above the center sills between the plates and attached to the sides thereof.

- 50 19. In a car-frame, the combination, with the center sills and side sills, of cross-bearers located between the body-bolsters and comprising vertical side plates having portions rising above the side sills and center sills to 55 receive a tank, angle-bars passing across beneath the center sills and attached to the lower edges of said plates, and horizontal angle-bars passing across above the center sills and attached to the sides of said plates.

- 60 20. In a car-frame, the combination, with the side sills, of tank-supporting saddles comprising transverse vertical plates terminally attached to the side sills and rising above 65 said sills to meet the curve of the tank, and footboard-plates running along and secured

to the tops of the side sills, the saddle-plates being reduced in depth at their outer ends to permit said footboard-plates to pass over them.

21. In a car-frame, the combination, with 70 the center sills and side sills, of body-bolsters extending from the center sills to the side sills, head-blocks carried by the center sills, and longitudinal braces running from the bolsters to the head-blocks at each side of 75 the center sills.

22. In a car-frame, the combination, with 80 the center sills, side sills and end sills, of body-bolsters extending from the center sills to the side sills, and longitudinal brace-bars running from the bolsters to the end sills between the center sills and side sills.

23. In a car-frame, the combination, with 85 the center sills, side sills and end sills, of body-bolsters extending from the center sills to the side sills, longitudinal brace-bars running from the bolsters to the end sills between the center sills and side sills, and head-blocks resting upon and secured to the center sills and brace-bars.

24. In a car-frame, the combination, with 90 the center sills, side sills and end sills, of body-bolsters extending from the center sills to the side sills, longitudinal brace-bars running from the bolsters to the end sills between the center sills and side sills, head-blocks resting upon and secured to the center sills and brace-bars, and brace-plates running from the bolsters to the head-blocks above the brace-bars.

25. In a car-frame, the combination, with 95 the center sills, side sills and end sills, of body-bolsters extending from the center sills to the side sills, pairs of longitudinal brace-bars running from the bolsters to the 100 end sills between the center sills and side sills, head-blocks resting upon and secured to the center sills and brace-bars, and brace-plates running from the bolsters to the head-blocks with their lower edges fastened between the members of the brace-bar pairs.

26. In a car-frame, the combination, with 105 the body-bolsters and head-blocks, of longitudinal brace-plates running from the bolsters to the head-blocks at each side of the 110 center.

27. In a car-frame, the combination, with 115 the body-bolsters and head-blocks, of longitudinal brace-plates running from the bolsters to the head-blocks, and tank-straps 120 having their ends secured to said plates.

28. In a car-frame, the combination, with the body-bolsters and head-blocks, of longitudinal brace-plates running from the bolsters to the head-blocks, and tank-straps 125 having their ends passed through said plates and held by angle-eyepieces on the inside thereof.

29. In a car-frame, the combination, with a tank, of supporting-saddles therefor com- 130

prising pairs of vertical plates, eyepieces fastened between said plates, and tank-straps having their ends passed through and held by said eyepieces.

5 30. In a car-frame, the combination with a tank, of supporting-saddles therefor comprising pairs of vertical plates, inclined cross-plates forming eyepieces fastened between said plates, and tank - straps having their ends passed through and held by said eye-pieces.

10 31. In a car-frame, the combination with

a tank and the center sills of the frame, of a stirrup-plate attached to the under side of said sills, a yoke surrounding the tank-dome, 15 and strap-bars on each side of the tank running from the yoke to said stirrup-plate.

In testimony whereof I have affixed my signature in presence of two witnesses.

WILLIAM F. KIESEL, JR.
